UNITED STATES PATENT OFFICE.

AUGUSTE CAMILLE EDMOND RATEAU, OF PARIS, FRANCE, ASSIGNOR TO
RATEAU TURBINE COMPANY, OF CHICAGO, ILLINOIS, A CORPORATION
OF WEST VIRGINIA.

BLOWING MACHINERY.

No. 827,750.

Specification of Letters Patent.

Patented Aug. 7, 1906.

Application filed December 24, 1902. Serial No. 136,455.

To all whom it may concern:

Be it known that I, AUGUSTE CAMILLE EDMOND RATEAU, a citizen of the Republic of France, residing at Paris, France, have invented a certain new and useful Improvement in Blowing Mechanism, of which the following is a full, clear, concise, and exact description.

My invention relates to a centrifugal fan or blower; and its object is to produce a device which will be adapted to be driven at very high rates of speed, as by direct connection to a turbine-engine. The rotary element or impeller-wheel of such a fan or blower must necessarily possess great strength because of the enormous centrifugal strains to which it is subjected.

My invention consists in an impeller-wheel comprising a plate having a series of radial blades projecting beyond its periphery, each blade being preferably provided with a strengthening-rib extending down its back.

The fan of my invention is designed more particularly for use in connection with turbine-driven apparatus, and hence in use is subjected to enormous centrifugal force due to the extremely high speed at which such fans are driven. I therefore form the impeller-wheel in one integral piece, as being thus less likely to be torn apart by centrifugal force. In practice I have found the impeller-wheel of my invention peculiarly adapted to withstand the effects of the high speed at which turbine-driven blowers are operated.

I will describe my invention more fully by reference to the accompanying drawings, in which—

Figure 1 is a side elevation, partly in section, of a blower embodying my invention with one section of the housing or casing removed. Fig. 2 is a section on line 2 2 of Fig. 1. Fig. 3 is a perspective view of the impeller-wheel.

Similar numerals of reference indicate similar parts throughout all the figures.

The impeller-wheel 1 is secured by a key 2 or in any other suitable manner to the shaft 3, which is driven in any desired manner. Said impeller-wheel is surrounded by a casing 4, which is formed to provide an air-inlet 5, opening centrally around the impeller-wheel, and a peripheral delivery-chamber 6, having a gradually-increasing cross-sectional

area in the direction of rotation of the wheel. The delivery-chamber terminates in an outlet 7.

The impeller-wheel 1 consists of a single piece of metal, the body portion of which is in the form of a plate or disk. A series of blades 8 are formed on said disk, each blade projecting on each side of the disk, preferably extending from a point near the hub 9 of the disk radially toward and beyond the periphery thereof. As shown most clearly in Figs. 2 and 3, the blades taper from their inner ends toward their outer ends to conform to the contour of the peripheral chamber adjacent thereto.

Each blade 8 is provided with a strengthening-rib 10 on its back extending to the outer end of the blade, which rib is formed by a radial extension of the central plate.

Having thus described my invention, I claim—

1. In a centrifugal fan, the combination with a plate constituting the body portion of the fan, of blades disposed on the face of said plate, and extending radially toward and projecting beyond the periphery thereof, and ribs forming continuations of said plate and extending down the backs of the blades to the outer ends thereof.

2. A rotary fan comprising a hub, a circular plate integral therewith, and a series of outwardly-tapering blades integral with said plate and projecting radially beyond the periphery of said plate; each blade having a portion extending laterally from each face of the plate, and a strengthening-rib forming a continuation of the plate.

3. An impeller-wheel formed of an integral piece and comprising a circular plate, a series of outwardly-tapering blades, each blade projecting on each side of the plate and extending radially from near the axis of said wheel toward and beyond the periphery of said plate, and strengthening-ribs extending from said plate down the backs of the blades.

In testimony whereof I have signed this specification in the presence of two subscribing witnesses.

AUGUSTE CAMILLE EDMOND RATEAU.
